UNITED STATES PATENT OFFICE.

ERNEST H. SCHMIDT AND CHESTER K. BROOKS, OF CLEVELAND, OHIO, ASSIGNEES TO THE NATIONAL MALLEABLE CASTINGS COMPANY, OF CLEVELAND, OHIO, A CORPORATION OF OHIO.

COUPLING-SHANK AND YOKE CONNECTION.

1,291,182.

Specification of Letters Patent. Patented Jan. 14, 1919.

Application filed April 9, 1915. Serial No. 20,333.

To all whom it may concern:

Be it known that we, ERNEST H. SCHMIDT and CHESTER K. BROOKS, citizens of the United States, residing at Cleveland, Cuyahoga county, Ohio, have jointly invented new and useful Improvements in Coupling-Shank and Yoke Connections, of which the following is a specification, reference being had to the accompanying drawings, in which—

Figure 1 is an elevation, partly in section, of a device constructed in accordance with our invention; Fig. 2 is a plan, partly in section, thereof; Fig. 3 is a section on lines III—III of Fig. 1; Fig. 4 is a section on lines IV—IV of Fig. 1; Fig. 5 is a section on lines V—V of Fig. 1; Fig. 6 is a perspective view of the yoke; Fig. 7 shows details of the removable members; Fig. 8 is an elevation, partly in section, of a modification of our invention; Fig. 9 is a plan thereof, partly in section, and Fig. 10 is a detail of the removable members.

Our invention relates to coupler shank and yoke connections, and consists in providing a horizontal yoke with a hooded forward end into which the coupler liner block is inserted from the forward side, and in which it is secured by removable means bearing between the yoke and the coupler liner block. The horizontal arrangement of the yoke also permits the draft gear to be removed from below without disturbing the coupler and yoke in their position on the car, and, when the draft gear has been removed, the securing means between the coupler and yoke may be removed and the coupler taken down, independently of the yoke. Our invention also consists in the construction and coöperation of the various parts which we shall hereinafter describe and claim.

Referring to the drawings, the coupler A is of the usual character, having a liner block 2 and the usual vertically-extending rivet holes 3. B is the yoke, which is arranged horizontally, that is, with its arms 4, 4 in the same horizontal plane, and which at its forward end, terminates in a hood 5, open at front and rear, the walls 6 of which flare outwardly so as to permit the coupler to angle laterally relative to the yoke B. The inner surfaces of the hood 5 are a sufficient distance apart to allow the passage of

the coupler liner block 2 between them, and the rear edges 7 of the top and bottom of the hood 5 act as pulling faces and are preferably arc-shaped. When the coupler has been inserted into the yoke it is held in position by a removable member or members 8, of which I have shown two, one above and the other below the liner block, each of which is provided with an upwardly-extending lip 9 having an arc-shaped forward face 10 which bears against the corresponding arc-shaped face 7 of the hood 5 and with a downwardly-extending lug 11 at its forward end, the rear face of which is arranged at right angles to the line of draft, against which the forward face 12 of the liner block 2 has a pulling bearing. Each removable member 8 on the face which engages the horizontal surface of the coupler liner block, preferably has a plurality of bosses 13, adapted to fit into the rivet holes 3 of the coupler liner block.

In applying the device to the car, the yoke is put into position first, with its arms 4—4 lying in the same horizontal plane, and the coupler butt is then inserted into the hood 5 of the yoke and pushed rearwardly until there is a space between the rear edges 7 of the hood, and the forward vertical faces 12 of the coupler liner block. The removable members 8 are then placed in position above and below the liner block and in engagement with the horizontal faces and vertical front edges thereof, and the coupler is then pulled forwardly again, so that the arc shaped faces 10 of the members 8 engage the arc shaped rear faces 7 of the hood 5. The draft gear or cushioning mechanism C, which may be of any desired type and which I have shown in the form of a friction barrel, may then be inserted between the yoke arms 4 from below, and when it has been raised to the proper position between the yoke arms 4 with its followers 15 or equivalent means bearing against the stops 16, the bottom plate 17 may be attached, and the device is then ready for service.

In draft it will be seen that the coupler liner block 2 bears against the rear faces of the lugs 11 of the removable members 8, and the arc-shaped faces 10 of the removable members in turn pull against the faces 7 of the hood 5 of the yoke, thus pulling the yoke forwardly with it. The coupler is

free to move laterally the amount allowed by the flaring side walls of the hood, while the removable members 8, as their arc-shaped faces 10 are preferably curved about 5 a center, rearward of the coupler butt, will pivot about such center and slide along the curved faces 7 of the hood.

Under buffing stresses the coupler shank moves rearwardly within the hooded forward end of the yoke and compresses the shock absorbing mechanism. If the removable members 8 are provided with bosses 13 seating in the rivet holes 3 of the coupler liner block, they will travel rearwardly with 15 the coupler shank, within the yoke hood, to the extent permitted by the shock absorbing mechanism.

In Figs. 8, 9 and 10 we have shown a modified form of the hood and removable member. The hood 5' has at its forward end inwardly extending lugs 20 having arc-shaped bearings which engage the correspondingly shaped forward faces 21 of the removable members 8'. Each removable 25 member 8' has a face 22 arranged at right angles to the line of draft, against which the forward face of the liner block has a pulling bearing. Each removable member 8' has also a rearwardly extending portion 30 23 which very nearly fills the space between the top of the hood 5' and the liner block, or the bottom of the hood 5' and the liner block as the case may be. A forward extension 24 of the member 8' fits with the 35 same clearance between the inner faces of the lugs 20 and the shank of the coupler.

Our invention is of particular advantage, since it provides for the piecemeal removal and replacement of the draft gear, coupler, 40 yoke and various other parts, thus occasioning great saving of time and labor and making the device much easier to repair than the form of rigging using the vertical yoke now in common use.

45 It is also to be seen that the hood at the forward end of the yoke greatly strengthens the yoke, and the use of the filler blocks for securing the coupler in the yoke forms a connection which makes the disengagement of the parts extremely easy and simple.

The terms and expressions which we have employed herein are used as terms of description and not of limitation, and we have no intention, in the use of such terms and 55 expressions, of excluding any mechanical equivalents for the features shown and described, but recognize that various modifications are possible within the scope of the invention claimed.

60 What we claim is:

1. A coupler yoke having its arms arranged in a horizontal plane and having a hooded forward end adapted for reception of a coupler liner block from the forward 65 side, the hooded forward end of the yoke

having webs joining the yoke arms and extending above and below the coupler liner block, and a securing member adapted to be inserted between the liner block and the yoke, said securing member being adapted to transmit draft strains from the coupler 70 to the yoke.

2. A coupler yoke having the forward end arranged in a vertical plane in the form of an integral four-sided hood open at front 75 and rear; and having a body portion arranged in a horizontal plane integral with the sides of the hood closed at the rear end and open above and below; the hood being adapted for the reception of a coupler liner 80 block from the forward side and having horizontal pulling bearings arranged in planes parallel to the plane of the body portion and above and below said body portion, and a removable member adapted for 85 insertion from the rear side of the hood between one of the pulling bearings of the hood and a forward face of the coupler liner block, and adapted to transmit draft strains from the coupler to the yoke. 90

3. A coupler yoke having the forward end arranged in a vertical plane in the form of an integral four-sided hood open at the front and rear and having a body portion arranged in a horizontal plane integral with 95 the sides of the hood closed at the rear end and open above and below, the hood being adapted for the reception of a coupler liner block from the forward side, the hood having horizontal pulling bearings arranged in 100 planes parallel to the plane of the body portion and above and below said body portion, a removable member adapted for insertion from the rear side of the hood, between one of the pulling bearings of the 105 hood and a forward face of the coupler liner block, and adapted to transmit draft strains from the coupler to the yoke, and shock absorbing mechanism set between the yoke arms and being removable vertically 110 from below without disturbing the connection between the yoke and the coupler.

4. A coupler yoke having the forward end arranged in a vertical plane in the form of an integral four-sided hood open at front 115 and rear and having a body portion arranged in a horizontal plane integral with the sides of the hood closed at the rear end and open above and below, the hood being adapted for the reception of a coupler liner 120 block from the forward side, and a removable member adapted for insertion between the liner block and the hood, said member being adapted to engage a rear edge of the hood and to transmit pulling strains thereto 125 from the coupler liner block.

5. A coupler yoke having the forward end arranged in a vertical plane in the form of an integral four-sided hood open at front 130 and rear and having a body portion ar-

ranged in a horizontal plane integral with the sides of the hood closed at the rear end and open above and below, the hood being adapted for the reception of a coupler liner block from the forward side, and a removable member engaging the coupler liner block and having an arc-shaped bearing intended to pull against an arc-shaped rear edge of the hood, said arc-shaped bearing being adapted to allow lateral angling 10 between the coupler and yoke.

6. A coupler yoke having the forward end arranged in a vertical plane in the form of an integral four-sided hood open at front 15 and rear and having body portion arranged in a horizontal plane integral with the sides of the hood closed at the rear end and open above and below, the hood being adapted for the reception of a coupler liner block 20 from the forward side, and a removable member adapted for insertion between the liner block and the hood from the rear-

ward side of the hood, said member having at one end an upwardly-extending lug engaging the rear edge of the hood and at 25 the other end a downwardly-extending lip engaging the forward face of the liner block.

7. A coupler yoke having its arms arranged in a horizontal plane, webs at the 30 forward ends of the arms also arranged in horizontal planes and connecting the tops and bottoms of said arms to form a box-like structure open at both ends and adapted for the reception of a coupler liner block 35 from its forward side, a removable member adapted for insertion between the liner block and the webs, said member engaging a rear edge of a hood and being adapted to transmit pulling strains thereto from the 40 coupler liner block.

ERNEST H. SCHMIDT.
CHESTER K. BROOKS.
